OVERCAP FOR AN AEROSOL PACKAGE OR THE LIKE

George B. Fahlstrom, Amherst, N.Y., assignor to Animal Repellents, Inc., Buffalo, N.Y.

Filed June 9, 1965, Ser. No. 85,641

Term of patent 14 years

(Cl. D58—26)

FIG. 1.

FIG. 2.

FIG. 3.

FIG. 4.

FIG. 5.

FIG. 1 is a front elevational view of an overcap for an aerosol package or the like, showing by new design therefor;

FIG. 2 is a side elevational view thereof;

FIG. 3 is a rear elevational view thereof;

FIG. 4 is a top plan view thereof; and

FIG. 5 is a bottom plan view thereof.

The side not shown is identical to that shown in FIG. 2. I claim:

The ornamental design for an overcap for an aerosol package or the like, substantially as shown and described.
